(57) **CLAIM**

The ornamental design for a light fixture, as shown and
described.

DESCRIPTION

FIG. 1 is a bottom perspective view of a light fixture in
accordance with my design;

FIG. 2 is a side elevation view of the light fixture in accordance
with my design, all side views being substantially
identical;

FIG. 3 is a top plan view of the light fixture in accordance with
my design; and,

FIG. 4 is a bottom plan view of the light fixture in accordance
with my design.

The broken lines showing environmental structure are for
illustrative purposes only and form no part of the claimed
design.
